UNITED STATES PATENT OFFICE.

FRANCIS H. HAYERS, OF HUTCHINSON, KANSAS.

HYDROCARBON-BURNER.

1,009,743.

Specification of Letters Patent. Patented Nov. 28, 1911.

Application filed March 3, 1911. Serial No. 612,148.

To all whom it may concern:

Be it known that I, FRANCIS H. HAYERS, a citizen of the United States, residing at Hutchinson, in the county of Reno and State of Kansas, have invented certain new and useful Improvements in Hydrocarbon-Burners, of which the following is a specification.

My invention relates to improvements in hydrocarbon burners.

My invention is particularly adapted for use in burning crude oil.

The object of my invention is to provide a burner which is simple in construction and efficient and economical in operation, and which may be readily adjusted to burn different grades of oil.

The novel features of my invention are hereinafter more fully described and claimed.

In the accompanying drawings which illustrate the preferred form of my invention, Figure 1 is a perspective view of the burner. Fig. 2 is a top view of the drip pan. Fig. 3 is a top view of the boiler with the cover removed. Fig. 4 is a side elevation of the vapor discharge pipe and lock nut. Fig. 5 is a vertical section of the burner. Fig. 6 is a vertical section at right angles to Fig. 5.

Similar reference characters denote similar parts.

The numeral 1 denotes a drip pan having in the bottom portion one or more vertical air inlets 2, the side wall of the drip pan having one or more outlets 3 for the discharge of the products of combustion. On the inner side of the wall of the drip pan are lugs 4 which support a pan like member 5 of a steam boiler, said member being, preferably, of less outside diameter than the inner diameter of the upper end of the drip pan 1. The member 5 has its upper edge mounted in an annular groove in the lower side of a cover member 6. The bottom of the member 5 is provided with an upwardly raised portion 7 having a central vertical steam discharge outlet 8 the lower end of which is preferably screw threaded and has vertically adjustable therein the upper end of a vertical vapor discharge pipe 9, the upper end of which is externally screw threaded and fitted to the threaded portion of the outlet 8.

The bottom of the drip pan 1 is provided centrally with a raised conical boss 10 the upper end of which projects into

the lower discharge end of the pipe 9, said pipe being vertically adjustable toward and from the boss 10 by being turned in the proper direction in the outlet 8. A lock nut 11 may be mounted on the threaded part of the pipe 9 for clamping against the under side of the member 5 to secure the pipe 9 in the position to which it may be adjusted.

The parts are held together by a vertical bolt 12 which extends through a vertical hole in the cover member 6 and through the outlet 8 and pipe 9, the lower threaded end being fitted in a vertical threaded hole in the apex of the boss 10, and the upper end 70 having a head which bears on the upper side of the cover member 6.

The pipe 9 is provided with a fuel passage 13 which preferably is located near the lower end of the pipe and inclines downwardly and inwardly so as to project a jet against the boss 10, the flaring surface of which serves to diffuse the jet of fuel. Connected to the inlet end of the passage 13 is a fuel conductor 14 which may be connected to any suitable source of supply, not shown.

The member 5 is provided with a hole in which is secured the discharge end of a conductor 15 the other end of which is connected to a source of water supply, not shown. The bottom of the member 5 is preferably provided with a boss 16 which is provided with a vertical hole 17 for the escape of water. The hole 17 is located above a portion of the bottom of the drip pan 1, 90 which portion is inclosed by a vertical flange 18 the ends of which connect with the side wall of the drip pan and form a basin 19, the bottom of which is provided with a vertical hole 20 for the escape of water collected in said basin.

In operating my invention, oil is first poured upon the cover member 6 and permitted to flow therefrom into the drip pan 1, where it is ignited to initially heat the burner. When the burner has been thus heated, oil is permitted to flow into the pipe 9 from the conductor 14. Water is also permitted to enter the boiler member 5 through the conductor 15. The hole 17 in the boss 16 is provided so as to permit water in the member 5 to escape when the water rises to a level above the top of the boss 16. The water so escaping will pass into the basin 19 from which it will escape by the hole 20. The water in the member 5 will be converted by the heat of the burner into steam,

which will pass through the outlet 8 and into the pipe 9 where it will mix with the oil vapor produced by the vaporizing of the fuel entering the pipe 9 through the passage 13. The mixed steam and oil vapor will pass out from the lower end of the pipe 9 and will be deflected and diffused by the conical boss 10 so that it will readily mingle with the air entering the drip pan 1 through the openings or inlets 2. The products of combustion will pass from the pan 1 around the member 5 and through the outlets 3, thus heating the boiler and the other parts of the burner, whereby the operation 15 is made continuous.

By removing the conductors 14 and 15 and the bolt 12, the parts may be separated so as to permit any desired adjustment of the lock nut 11 and pipe 9 to suit the particular quality or kind of fuel employed. After such adjustment the parts may be again assembled in operative relation to each other, after which the burner may be operated as I have already described. By vertical adjustment of the pipe 9, the space between said pipe and the conical boss 10 may be varied to suit the required conditions. Such steam as passes from the small hole 17 will mingle with the products of combustion and with the vapor and steam discharged from the pipe 9.

I do not limit my invention to the structure illustrated and described, as many modifications, within the scope of the appended claims, may be made without departing from the spirit of my invention.

Having thus described my invention, what

I claim and desire to secure by Letters Patent, is:—

1. A hydrocarbon burner having a drip pan provided with a conical deflecting boss and having side walls provided with an air inlet, a boiler supported by said drip pan above said air inlet, the boiler having a vertical discharge outlet, a vapor discharge pipe vertically adjustable in said outlet and having a discharge end into which said boss extends, the vapor pipe having a fuel passage discharging into the interior of the vapor pipe, and a securing device extending through the said outlet and vapor pipe and connecting the boss and boiler.

2. A hydrocarbon burner having a drip pan provided with a conical deflecting boss, a boiler supported by the drip pan and having a vertical outlet in axial alignment with the center of the boss, said outlet being screw threaded, a vertical vapor pipe having a screw threaded upper end adjustably fitted in said threaded outlet and having its discharge end encircling the apex of said boss, the vapor pipe having an oil passage leading to its interior, and a bolt extending through the boiler and through said vapor pipe and secured to said boss for clamping the boiler to the drip pan.

In testimony whereof I have signed my name to this specification in presence of two subscribing witnesses.

FRANCIS H. HAYERS.
